UNITED STATES PATENT OFFICE.

JAMES H. RAND, OF NORTH TONAWANDA, NEW YORK.

INDEX.

1,302,848.

Specification of Letters Patent.

Patented May 6, 1919.

Application filed April 15, 1918. Serial No. 228,563.

To all whom it may concern:

Be it known that I, JAMES H. RAND, a citizen of the United States of America, and resident of North Tonawanda, in the county 5 of Niagara and State of New York, have invented new and useful Improvements in Indexes, of which the following is a specification.

This invention relates to index devices and 10 more particularly to overlapping card indexes of the so-called visible index type, wherein a series of hinged, index elements are supported in a frame in overlapped, spaced relation with their free margins projecting one beyond another to display identifying characters.

Other features of the invention will hereinafter be described and pointed out in the claims.

20 In the accompanying drawings which illustrate one embodiment of the invention,—

Figure 1 is a face view of an index device containing the invention;

25 Fig. 2 is a section on line 2—2 of Fig. 1; Fig. 3 is a face view of one of the index elements;

Fig. 4 is a section on line 4—4 of Fig. 3; Fig. 5 is an enlarged sectional detail on

30 line 5—5 of Fig. 3; Fig. 6 is a transverse section on line 6—6 of Fig. 1; and

Fig. 7 is a detail of a modification.

The frame may be of any usual or preferred construction, and as herein shown 35 consists of a back A of sheet metal, having inwardly bent flanges a, a, forming opposed channels.

A series of similar index elements constituting card-holders are supported in the 40 frame, each comprising a base portion 1 and a free portion 2, integrally formed of cardboard or other suitable sheet material divided by a crease 3, which constitutes a hinge on which the free portion may be 45 swung away from the frame.

The base portion 1 has a pair of lateral 50 projections 4, 4, which extend into the channels of the frame formed by flanges a, a, and hold the base portions 1 flatwise in the frame, permitting the card-holders however to slide lengthwise of the frame. The base portion 1 is provided with supporting and spacing tabs 5, preferably cut from the body 55 of the sheet material and bent a little to the rearward. Said tabs engage the edge of the

base portion of the next adjacent card-holder and hold the card-holders in overlapped spaced relation. It will be observed also that the successive base portions of the index elements overlap one another, thus lending support one to another and making it possible to use a single ply of thinner and less stiff sheet material than would be possible if the base portions were not mutually 60 supported. The lowermost element of the series may be supported by a filler card C at the bottom of the frame (Fig. 2).

At the outer edge of each free portion 2 is means to engage the margin of a card insert 6, consisting preferably of a strip of transparent sheet celluloid 7 folded over and attached to the edge 2, forming a pocket and sheath to receive the outer edge of the card insert. The inner edge of the card insert 6 70 terminates near, and at any rate not beyond, the hinge 3. When the free portion 2 of the card-holder is swung upward on its hinge the top or inner edge of the card-insert, instead of sliding up on the card-holder as it 75 would do if the card-insert extended beyond the hinge, will remain in position on the free portion of the holder, and its top or inner edge will engage the crease or hinge 3 and hold the card insert against dislodgment. This construction also prevents the necessity of providing a lug or tongue on the card-holder to engage the top of the card insert and hold it in place, as has heretofore been the practice. The crease or 80 hinge 3 performs the functions of such lug, reduces the thickness of the index structure as a whole, and cheapens the cost of manufacture.

The body of the card-holders is preferably made of cardboard, while the tip or sheath 7 is of sheet celluloid. These materials possess different coefficients of expansion, with the result that they expand and contract unequally with variations of 95 temperature and humidity, frequently causing one member or the other to buckle or pucker. To overcome this I provide fasteners at the ends of sheath or strip 7 for attaching the members together, with provision to permit relative movement of expansion and contraction between them. The preferred structure for attaining this end comprises a fastener in the form of a loop or link 8 of wire, one end of which is attached to the body of the card-holder outside of the area covered by the strip 7, while 100 105 110

the other end is attached to the strip 7 and passes through an enlarged aperture 9 in the card 2, said aperture being large enough to permit freedom of play of the fastener 5 therein sufficient to allow for relative movements of expansion and contraction between the members. The ends of the links 8 which pass through the respective members are pivoted therein so that the links will 10 swing inward and outward as the strip contracts or expands on the card. The enlarged aperture 8 might be placed in the strip 7 instead of in the card; or the apertures 9 might open through the sides of the card 15 as shown in Fig. 7 instead of being holes as in Figs. 1 and 3; and other forms of fastener might be used, so long as freedom of play between the fastener and one at least of the members is provided, to admit of 20 greater expansion or contraction of one member than the other to prevent buckling or warping. Moreover this feature is applicable to other kinds of card-holders, or other index parts, wherein a similar difference 25 of expansion and contraction between the parts fastened together results in the buckling or warping of one of the parts.

I claim:

1. An index device comprising a frame 30 and a series of index elements supported in the frame in overlapped spaced relation, each comprising a base portion and a free portion hinged to the base portion, the base portions being held flatwise in the frame 35 and each having means for engaging the edge of the next adjacent base portion to hold said elements in spaced relation with their base portions overlapping one another, whereby the base portions are mutually 40 supported and stiffened one by another.

2. An index device comprising a frame and a series of index elements supported in the frame in overlapped spaced relation, 45 each comprising a base portion and a free portion hinged to the base portion, said parts being integrally formed of sheet material and the base portion consisting of a single ply of such sheet material, the base 50 portions being held flatwise in the frame and each having means for engaging the edge of the next adjacent base portion to hold said elements in spaced relation with their base portions overlapping one another, 55 whereby the base portions are mutually supported and stiffened one by another.

3. An index device comprising a frame and a series of index elements supported in the frame in overlapped spaced relation, 60 each comprising a base portion and a free portion hinged to the base portion, the base portions being held flatwise in the frame and each having supporting and spacing tabs in a position spaced from the edge thereof 65 for engaging the edge of the next adjacent

base portion to hold said elements in spaced relation with their base portions overlapping one another, whereby the base portions are mutually supported and stiffened one by another.

70

4. An index device comprising a frame and a series of card-holders supported in said frame, each comprising a base portion held flatwise in the frame and a free portion hinged to the base portion, the base portion being provided with supporting and spacing tabs in a position spaced from the edge thereof and adapted to engage the edge of the base portion of the next adjacent card-holder, to hold said card-holders 80 in overlapped spaced relation, means at the outer edge of the free portion to engage the margin of a card insert, and a card insert one margin of which is held by said engaging means and the opposite margin of which terminates not beyond the hinge, whereby the card insert will remain in position on the free portion of the holder when the same is swung on its hinge.

75

5. An index device comprising a frame 90 and a series of card-holders supported in said frame, each comprising a base portion held flatwise in the frame and a free portion hinged to the base portion, the base portion being provided with supporting and 95 spacing tabs in a position spaced from the edge thereof and adapted to engage the edge of the base portion of the next adjacent card-holder, to hold said card-holders in overlapped spaced relation, means at the outer edge of the free portion to engage the margin of a card insert, and a card insert one margin of which is held by said engaging means and the opposite margin of which terminates near the hinge, whereby the engagement of the edge of the card insert with the hinge will hold the card insert in position and prevent the dislodgment of the same when the free portion of the holder is folded on its hinge.

100

6. An index element comprising a base portion having laterally extending projections adapted to engage the channels of a frame, and a free portion depending from the lower edge of the base portion and divided from the base portion by a crease forming a hinge, all of said parts being integrally formed of sheet material.

105

7. An index element comprising a base portion having laterally extending projections adapted to engage the channels of a frame, a free portion divided from the base portion by a crease forming a hinge, and supporting and spacing tabs cut from the body of the base portion, all of said parts being integrally formed of sheet material.

110

8. An index element comprising a card, a sheath of sheet celluloid on the card, and fasteners passing through both sheath and card attaching the sheath to the card and 130

adapted to permit relative movement of expansion and contraction between the sheath and card.

5. An index element comprising a card, a sheath of sheet celluloid on the card, and a fastener for attaching the sheath to the card comprising a link one end of which is attached to the card and the other end to the sheath, whereby relative movement of expansion and contraction is permitted between the sheath and card.

10. An index element comprising a card, a sheath of sheet celluloid on the card, and a fastener for attaching the sheath to the card, one of the members through which the fastener passes having an aperture adapted to permit freedom of play of the fastener therein.

15. An index element comprising a card, a sheath of sheet celluloid on the card, and a fastener for attaching the sheath to the card comprising a link, one end of which is attached to the card outside of the area covered by the sheath, and the other end of which is attached to the sheath and passes through an aperture provided therefor in the card, said aperture being adapted to permit freedom of play of the fastener therein.

20. An index device comprising a body and a strip of sheet material having differ-

ent coefficients of expansion, and fasteners passing through both of said members and attaching the two members together, adapted to permit relative movement of expansion and contraction between them.

35

25. An index device comprising a body and a strip of sheet material having different coefficients of expansion, and fasteners attaching the two members together comprising a link one end of which is pivotally attached to the body outside of the area covered by the strip, and the other end of which is attached to the strip and passes through an aperture provided therefor in the body, said aperture being adapted to permit freedom of play of the fastener therein.

40

30. An index device comprising a body and a strip of sheet material having different coefficients of expansion, and a fastener passing through both of said members and attaching the two members together, one of said members being provided with an aperture through which the fastener passes adapted to permit freedom of play of the fastener therein.

45

35. Signed by me at Boston, Massachusetts, this twelfth day of April, 1918.

JAMES H. RAND.
